Patented Mar. 19, 1918.

UNITED STATES PATENT OFFICE.

SALLY M. SPENCER, OF FLAGSTAFF, ARIZONA.

NOSE-BAG.

1,260,087.

Specification of Letters Patent. Patented Mar. 19, 1918.

Application filed June 22, 1915. Serial No. 35,651.

To all whom it may concern:

Be it known that I, SALLY M. SPENCER, a citizen of the United States, residing at Flagstaff, in the county of Coconino and State of Arizona, have invented new and useful Improvements in Nose-Bags, of which the following is a specification.

This invention contemplates the provision of a nose bag which can be comfortably supported by the animal, and having an enlarged opening in the body portion thereof for supplying a large quantity of air to the bag for ventilating purposes, the opening being covered by a flexible interwoven 10 foraminated fabric whereby the bag can be collapsed when not in use without injuring the mesh of the fabric.

The invention resides in the specific construction and arrangement of parts herein- 20 after more fully described and claimed.

In the drawing forming part of this application like numerals of reference indicate similar parts in the several views and wherein: —

25 Figure 1 is a view of a bag showing the same in use.

Fig. 2 is a vertical sectional view.

Fig. 3 is a front elevation.

30 Fig. 4 is a top plan view of the bag ex- tended.

Referring more particularly to the drawing 5 indicates the bottom of the bag which may be constructed from any suitable material, preferably heavy leather, and formed 35 to provide a vertical circumferential flange 6 to which the lower edge of the body portion 7 is secured in any suitable manner. The body portion is constructed from flexible material, preferably canvas of the proper 40 weight, and has secured to the sides thereof at diametrically opposite points a loop adjusting strap 8, the latter being terminally connected to the circumferential flange 6 of the bottom. By reason of this arrangement 45 the strap serves to reinforce the body portion 7, but is primarily intended for supporting the bag in proper position with relation to the mouth of the animal. The upper edge of the body portion is provided 50 with a circumferential series of spaced vertically disposed slits 9 through which an adjustable and flexible band 10 is threaded, the intermediate portion of which is disposed within the bag approximately in a 55 line with the longitudinal center thereof,

the band being adapted to be drawn about the nose of the animal, as well as to contract a portion of the upper edge of the bag to assist the strap 8 in supporting the bag in proper position as clearly shown in Fig. 1. 60 With the band 10 adjusted, a ventilating space 11 is provided in advance thereof.

The front face of the bag is provided with a longitudinally extending opening, gradually increasing in width toward the 65 bottom thereof, said opening being covered by a flexible interwoven foraminated fabric 12 of suitable mesh, with a view of supplying a large quantity of air to the bag for ventilating purposes, the fabric being secured to the inner marginal edges of the opening in any suitable manner, preferably 70 by stitching. Secured to the fabric 12 along the longitudinal center thereof is a strip of cloth or other suitable material 13 forming a backing for the reinforcing strap 14 which latter is secured to the strip 13 and also terminally secured to the bag above and below the opening. Similarly extending across the transverse center of the fabric 75 is a strip 15 forming a backing for the reinforcing strap 16 which is secured to the strip 13 and also terminally secured to the bag at the opposite sides of the opening in the bag. By reason of the fact that the venti- 80 lating element or fabric 12 is formed from flexible material, it will be manifest that the bag may be collapsed or folded in any desired manner when not in use without injuring the fabric in any manner which 85 would be the result if foraminated wire or a perforated sheet of metal was used instead of the fabric 12. In addition to this fact the fabric is effectively reinforced by means of the strips 13 and 15 and the straps 90 14 and 16 respectively. By constructing the foraminated element 12 from flexible material, a relatively large ventilating opening 95 may be provided in the bag, and at the same time permit the bag to be collapsed without 100 injury to the member as hereinabove stated, the relatively large opening together with the space 11 in the upper edge of the bag permitting a large quantity of air to be supplied to the bag, thereby allowing the animal 105 to breath more easily than under ordinary conditions and feed in comfort.

It is believed that from the foregoing description the nature and advantages of the invention will be thoroughly understood 110

without requiring a more extended explanation and therefore the same has been omitted.

What is claimed is:—

- 5 1. In a device of the class described, a bag having a collapsible body provided with a tapered opening in the front thereof and a flexible reticulated covering therefor, crossed flexible stays having connection with said covering and terminally connected with said body, and means for retaining said bag in applied position including an adjustable band threaded through the rear portion of said body to provide a nose engaging loop 10 therein above said opening.
- 15 2. In a device of the class described, a bag having a flexible and collapsible body provided with a longitudinally extending opening in the front thereof gradually in-

creasing in width toward its lower end, 20 flexible stays connected with the body to cross said opening both longitudinally and transversely, a flexible reticulated closure for said opening having connection with said body and stays, a flexible attaching member having a portion thereof threaded through the rear portion of said body to alternately lie interiorly and exteriorly thereof and forming a nose engaging loop within said body above said opening, and 25 means adjustably connecting the ends of the attaching member.

In testimony whereof I affix my signature in presence of two witnesses.

SALLY M. SPENCER.
